ART OF AND MEANS FOR CUTTING
LEATHER

Emanuel Berkowitz, Brooklyn, N. Y.

Application April 23, 1932, Serial No. 607,055

10 Claims. (Cl. 164—19)

This invention relates to the art of, and means for cutting from leather and the like, parts of various shapes, such as are adapted for use as soles, heels, shanks, counters and other parts of 5 shoes.

One of the great difficulties in the art of cutting leather is that leather, unlike most other materials in sheet or web form such as metal, textiles, paper, and the like, is not adapted economically 10 to be fed and cut continuously by automatic machinery, such as may be used for cutting or stamping other materials. While leather is produced in sheets or "sides", being usually animal hides or skins, it is well known that the thickness of any 15 given hide is not uniform throughout but varies considerably from head to butt. Furthermore, defects in the hide due to the method of procuring and making the leather may appear at some unexpected point in the hide. For these reasons, any 20 methods or means for cutting the leather should be so adaptable or flexible, or in other words, adjustable as to meet the peculiar requirements for economical cutting resulting from lack of uniform thickness and defects at unexpected points.

25 My invention therefore contemplates the provision of leather cutting means adjustable during operation thereof to cut parts differing in width from different parts of the hide, to correspond to the thickness of the hide at the particular place 30 from which the part is cut. My invention further contemplates the provision of improved cutting knives, enabling the cutting of one or more of the desired parts at a time, or of a portion of one part and a portion of a succeeding part simultaneously, 35 at high speed, and permitting the ejection of waste pieces from the hide, said knives being so designed as to enable the cutting of the desired parts or portions thereof with a minimum amount of labor and with substantial economy of material.

40 My invention further contemplates improvements in the art of cutting leather so as to avoid the necessity for marking patterns of the parts on the hide, and contemplates the provision of means for accomplishing these ends. My invention further 45 contemplates the provision of leather parts for shoes so designed as to permit cutting said parts from the hide economically and at high speed and with a considerable saving of material.

The various objects of my invention will be clear 50 from the description which follows, and from the drawings, in which,

Fig. 1 is a top plan view of a leather cutting machine to which my invention has been applied.

Fig. 2 is a side elevation of the same.

Fig. 3 is a side elevation on an enlarged scale of

the adjusting means for determining the width of the part to be cut from the hide while the machine is in operation.

Fig. 4 is a similar view of a modified form of the same. 5

Fig. 5 is a front elevation of the knife used in the machine, and of the support therefor.

Fig. 6 is a side elevation of the same.

Fig. 7 is a bottom plan view of the same.

Fig. 8 is a vertical section of a modified form of 10 knife support wherein means are provided for insuring the ejection of waste pieces.

Fig. 9 is a similar view of the same, showing a modified form of the waste-ejecting members.

Fig. 10 is a similar view of the same, showing 15 another modified form of the waste-ejecting members.

Fig. 11 is a plan view of a leather strip showing the shapes of the cuts made by two sets of knives in producing half soles alternately in inverted relation, one set of cuts representing one set of knives being shown in full lines, and the other in dash-dot lines. In the remaining figures, full lines and dash-dot lines are similarly used to indicate the 20 knife shapes and the cuts made thereby. 25

Fig. 12 is a similar view of a strip and of the shapes of cuts and of the single set of knives to cut half soles in the same corresponding position from the strip.

Fig. 13 is a similar view of a strip showing the 30 shapes of the cuts and knives used in cutting top lifts.

Fig. 14 is a similar view of a strip showing the use of two knives alternately for making intersecting cuts to cut half soles in the same position as 35 in Fig. 12.

Fig. 15 is a similar view of a strip showing how the knives, making intersecting cuts produce the soles in the relation disclosed in Fig. 11.

Fig. 16 is a similar view of a strip showing in full 40 lines the shape of the knife and of the cut made thereby to produce a half sole with attached waste pieces, the uncut outline of the finished sole being shown in dotted lines.

Fig. 17 is a similar view of a strip showing 45 how counters may be cut therefrom by the use of one knife.

Fig. 18 is a similar view of a strip illustrating the cutting of shanks therefrom.

Fig. 19 is a similar view of a strip illustrating 50 in the same manner, the cutting of half soles with a partly attached waste piece.

Fig. 20 is a perspective view of the half sole produced by the knives and cuts of Fig. 19.

Fig. 21 is a plan view of a strip showing the 55

cutting of right and left soles therefrom, together with intermediate shanks and top lifts.

Fig. 22 is a similar view of a strip illustrating in the same manner the knives and the cuts made in cutting overlapping half soles with economy.

Fig. 23 is a similar view, illustrating in the same manner, the cutting of half soles in inverted relation with intermediate top lifts.

10 Fig. 24 is a similar view of a strip showing in the same manner, the cutting of mated half soles in inverted relation.

15 Fig. 25 is a similar view of a strip showing, in the same manner, another arrangement of the half soles on the strip, and the knives and cuts made thereby.

20 Fig. 26 is a similar view of a pair of mated half soles such as may be cut from a strip by designing the knives so as to leave a non-cutting gap between certain portions of the knives illustrated in Fig. 12.

Fig. 27 is a similar view of a slightly modified form of mated soles cut in a similar manner.

25 Fig. 28 is a similar view of a pair of mated soles in inverted relation such as may be cut by leaving a non-cutting gap in the knives illustrated in Figs. 11 and 24.

30 Fig. 29 is a similar view of a pair of mated soles which may be cut from a strip by means of a pair of alternately acting knives, the waste pieces between the soles not being removed nor cut.

35 Fig. 30 is a similar view illustrating in full lines and in dash-dot lines, respectively, the shapes of the knives and of the cuts used where intersecting cuts are advantageous to cut half soles in end-abutting and inverted relation.

40 Fig. 31 is a similar view, showing in the same manner the shapes of the knives and of the cuts used in producing edge-corrugated heel pieces to be imbedded in rubber heels.

45 Fig. 32 is a plan view of a portion of a hide showing the cuts made therein to cut the hide first into irregularly shaped strips and then into soles with a minimum of waste.

Fig. 33 is a similar view, showing the formation of mated soles and the cutting thereof from a similar strip of double width.

50 Fig. 34 is a side elevational view similar to Fig. 2, illustrating the portion of a machine for operating the knives and showing three knives in the machine operated alternately.

55 Fig. 35 is a top plan view of part of the machine and particularly, the feed table thereof, illustrating the manner in which the strip of Fig. 32 is fed for cutting the strip into individual soles.

60 In that practical embodiment of my invention which I have illustrated by way of example, and referring particularly to Figs. 1 and 2, I have shown a leather cutting machine of the type known as a "Knox blocker" and disclosed in the patent to David Knox, No. 317,463, dated May 5th, 1885. The Knox blocker, as heretofore known, can only be used for making cuts completely across a strip by means of two knives operating alternately. Only incompletely shaped parts could therefore be cut on such machines. By means of my invention, however, the knives 70 are so shaped that they will make cuts of the desired intersecting or branched outline, enabling the cutting of completely shaped parts, as will be hereinafter explained in more detail. Furthermore, by making the stops for aligning the leading edge of the leather strip adjustable

during operation of the machine, I am enabled to compensate for desired variations in the width of the part to be cut in accordance with the varying thicknesses of the strip and of defects occurring in the strip. By providing an indicating gauge to determine the amount needed to swing the knife, I am further able to vary the widths or shapes of the parts to be cut without the necessity of first marking the strip with a pattern. I have also provided an improved machine whereby one knife may be used to make cuts heretofore impossible with the Knox blocker or a plurality of knives up to three are utilized to cut any desired variety of shapes in any desired relation.

15 As illustrated, the frame 40 supports the various operating instrumentalities including the oscillating frames 41 and 42 constituting the knife mountings, and in which the knives 43 and 44 are respectively mounted for pivotal adjustment, as by means of the bolt and nut pivot 45. The frames 41 and 42 are alternately oscillated to carry the knives into cutting position alternately. Between each or alternate cutting operations, the operator feeds the strip 46 so that the leading edge thereof engages the proper aligning stop 47 or 48. Each of the frames is oscillated by suitable mechanism such as the connecting rod 49, the crank disc 50, and suitable gear wheels 51, 52 interposed between and operatively connecting the pulley 53 to the crank disc in a manner well known in the art and hence which need not be described in detail. The knocker arms 54 are similarly oscillated at the proper time through the link 55, the rod 56 and the crank disc 57 to remove or knock out the part severed from the strip, from the table 58.

While the cutting machine just described is illustrated as having two knives of the proper form, it will be understood that only one of said knives may be used, if desired, by the removal either of the knife from its oscillatory frame, or by the disconnection or removal of one set of connecting rods 49, and that the machine may be speeded up so that the one knife operates as fast to make cuts as when both knives are used. It will further be understood that in some types of cutting, it may become desirable to use three knives cutting alternately, depending upon the shapes of the parts to be cut and the arrangement thereof. In the latter case, the third knife as 59 (Fig. 34) may be mounted on the vertically reciprocating cam rod 60 operating in the bearing 61 of the frame and carrying the cam roller 62. The cam roller and the knife 59 are normally urged upwardly on the rod 60. When the cam 63 on the shaft 64 is brought into engagement with the cam roller, the knife is caused to descend rapidly to make a cut. Said shaft 64 is driven by one of the gears 51 through 60 the gear 66 mounted on said shaft 64. The parts are so designed that the knife 59, carried on the frame 67 by means of the nut and bolt 68, is raised and lowered at sufficient speed and at the proper time to clear the oscillating knives 43 and 44, and to avoid interference with the operation thereof.

As has been hereinbefore indicated, means are provided for adjusting the positions of the stops 47 and 48, without the necessity for stopping the machine, and while the machine is operating. Said means, as shown in Figs. 1 and 2, includes the slide 70 on which said stops 47, 48 are mounted. The tongues 72 of said slide are supported for forward and rearward adjustment in suitable

horizontal grooves 71 in the bracket plate 272. Said bracket plate is provided with upright flanges as 73 by means of which it is secured to the frame of the machine. The adjusting means 5 further includes the link 14, secured at one end as 75 to the slide, and at its other end to the upper end 76 of the lever 17. The lower end 78 of said lever is mounted on the shaft 79 carried by the bearings 80 of the bracket 81.

10 As best seen in Fig. 1, a crank as 82 is secured to the shaft 79, said crank being connected by the rod 83 to the adjusting arm 84. As illustrated in Figs. 1 and 3, the shank 85, depending from the adjusting knob 86, passes through the arm 84 15 and terminates in a head 87 adapted to support the spring 88. Said spring is interposed between the head 87 and the arm 84 and serves to urge the adjusting knob 86 downwardly and the arm 84 upwardly into frictional engagement with the under side of the leg 89 of the bracket 90. At 20 its upper surface, the leg 89 is suitably indented or recessed as at 91 by a series of adjacent recesses, each adapted to receive the shoulder or 25 detent 92 of the adjusting knob, and thereby to maintain the adjusting knob normally in its adjusted position.

The shank 85 passes through a suitable slot 93 in the bracket leg 89, and is movable forwardly and rearwardly in said slot by first lifting the adjusting knob 86 slightly until the detent 92 leaves the recess 91, then moving the adjusting knob whereby the shank 85 moves in the slot 93, carrying the arm 84 with it, and through the connections previously described moving the slide 35 70 in the desired direction. When the adjusting knob has been moved the required distance and released, the spring carries the detent 92 into the recess 91, which is so shaped as to maintain said detent therein until removed therefrom. To 40 determine the amount of adjustment, the member 86 is provided with a pointer 94 pointing to a scale 95 which may be marked, if desired, with suitable indicia to indicate the width of the part which will be cut to correspond with the indication on the scale.

While it will be understood that the stops 47, 48 are each themselves separately adjustable in the lug 96 of the slide 70, as by means of the nuts 97, it will be clear that after said stops have been 50 set in their proper positions relatively to the slide, the adjusting knob 86 may be moved in the proper direction while the machine is running, to change the width of the parts, such as shoe soles, which are cut by the machine.

55 I have therefore made it possible to vary the width of the parts without interruption of the work and without the necessity for stopping the machine, or laying a pattern on the strip, or marking out the pattern on the strip and then 60 again starting the machine, as has hereinbefore been necessary to accomplish this end. The adjustment just described is particularly advantageous to cut wide soles or the like, such as soles of E or EE width from the central part of the hide 65 or strip, where the leather is usually thickest, without halting the machine.

As shown in Fig. 4, the knob or handle for adjusting the aligning stops may take a different form. As there shown, the rod 83 is connected 70 to the lever 296 by means of the bifurcated member 297. Said lever is pivoted to the bracket 90 as at 98 and terminates at its upper end in the hollow handle 100. Normally urged upwardly by the spring 101 and passing through the handle is 75 the spring-pressed finger piece 102, which ter-

minates at its lower end in a suitable pawl or 5 detent 103 normally urged upwardly by the spring 101 into engagement with the downwardly facing teeth 104 of the rack 105. In this form, the finger piece 102 is pressed downwardly against the action of the spring 101 to remove the pawl or 10 detent 103 from the rack teeth, whereafter the lever 296 may be swung about its pivot in either direction to operate the rod 83 and therethrough to move the slide 70 and the stops 47 and 48 into the desired adjusted position to enable the cutting of parts of the desired width.

It will be seen that power being applied to the pulley 53, the knives 43 and 44 are brought down alternately on to the table 58, to cut through the strip resting on the table.

It will be further be understood that the strip lies on the table with a side edge in engagement with the side guide 106. In operation, the strip 20 46 is first pushed rearwardly under the knife 43 or 25 44, a sufficient distance to permit the knife to trim the leading edge to the proper shape, after which the leading edge is pushed into contact with a selected one of the stops 47, 48 before the other knife 43 or 44 comes down to make the second 25 cut. Should a defect appear in the strip during the cutting operation, the strip is moved forward only a sufficient distance to cut off or clear the defect whereafter the operation is resumed. As the thicker part of the leather is reached, the 30 adjusting means are operated to move the stops 47, 48 rearwardly so as to cut wider soles.

It sometimes becomes necessary to swing either or both of the knives 43, 44 about their pivots 45, as when it is desired to cut parts of a different 35 shape or size. This is accomplished by stopping the machine, loosening the nut of the pivot 45, then swinging the knife about its pivot until the ends of the knife become arranged in the desired position. Heretofore, it has been customary to 40 mark the strip by means of a pattern, giving the desired shape or size. I have, however, made it unnecessary to mark the strip, by providing scales or indicating marks for the ends of the knife. The knife is swung until its ends are opposite 45 the selected points of the scales 107 on the gauges 108. Each of said gauges is mounted on the cross bar 109 as by means of a set screw 110.

The general form of the knives 43 and 44 will now be described. Since said knives are similar 50 to each other except for the contour of the edges thereof, the description of one and of the mounting therefor will suffice for both. Secured to the pivot bolt 45 is the knife-supporting block 111. (Figs. 5 to 10).

Suitable screws as 112 pass through said block 55 and into the upper edges of the knife blades 113, said blades being sufficiently thick at their upper edges for that purpose. As illustrated in Fig. 7, a branched knife blade is shown suitable for making the total arcuate full line cut 114 of Fig. 11, so as to complete the cutting of one half sole at each knife stroke and of the succeeding half soles in reversed relation.

The knife blade 113 is preferably made of a 65 single piece of material or of two pieces welded or otherwise permanently secured together to form a single cutting edge at the point 115 and a pair of branched or outwardly diverging cutting edges at other points. In the space 116 between the branches 117 and 118 of the cutting edges, I prefer to arrange means for insuring the separation of the waste piece 119 (Fig. 11) from the strip. As illustrated in Figs. 5, 6, and 7, said means takes the form of a knock-out block 70 75

120 secured to the lower end of the screw 121, the upper end 122 of which is arranged in the recess 123 of the knife block 111. The spring 124 is interposed between the upper face of the block 5 120 and the under face of the knife block 111 and normally urges the knock-out block 120 downwardly.

It will be seen that as the knife descends and cuts into the leather, the knock-out block 120 rests on the upper surface of the waste strip while the knife cuts through, the screw 121 being raised 10 relatively to the block 111, and the spring 124 being compressed. On the upward movement of the knife blade, the compressed spring 124 urges the screw 121 and the knock-out block 120 attached thereto against the waste piece with considerable force, and thereby serves to insure separation of the waste piece from the remainder of the strip.

20 It will be understood that as many screws 121 and springs 124 as may be found necessary are used, though a single screw and spring is shown for each of said knock-out blocks.

As illustrated, in Fig. 8, however, the springs, 25 screws and knock-out blocks may be eliminated and the waste piece allowed to enter the space between the branches 117 and 118 of the knife edges. The upper part of said space, however, is filled by the resilient member 129 preferably 30 of rubber or the like and having a bevelled or arcuate surface 125. It will be seen that as the waste pieces 119 enter the spaces between the knives, said waste pieces are gradually forced outwardly by the bevelled surface 125 in the 35 manner shown in dash-dot lines of Fig. 8 until they finally become dislodged and fall out of the spaces.

As shown in Fig. 9, the resilient block 126 of rubber or the like material may fill the entire 40 space between the knife edges 117 and 118. Said block operates in the same manner as the knock-out pieces 120, since owing to the resiliency of the block, the block is first compressed against the waste piece and on the upward movement of 45 the knife, is expanded and pushes upon the waste piece and ejects it from the strip.

As shown in Fig. 10, a central block 127 of any suitable material may be used provided with the upwardly and outwardly tapering surfaces 50 128. As the waste pieces 119 accumulate in the spaces between the knives, said waste pieces are gradually forced outwardly by the surfaces 128 until they are entirely dislodged and ejected.

It will be understood that the knife blades may 55 take any desired form, depending on the shapes and arrangements of the parts to be cut. I have found, however, that it is inadvisable to have a closed knife, that is, one of closed outline, to cut a section other than a waste piece from the strip. Such closed knives require an extraordinary amount of pressure when the area enclosed thereby is comparatively large, and further, make it impossible to avoid defects in the leather without wasting a complete part. In 60 what follows, therefore, I have shown a variety of knives for cutting various shapes and various arrangements of such shapes, but I have avoided using a closed knife of such shape that the enclosed part which it cuts out from a strip is a 65 finished part.

Referring now to Fig. 11, I have there shown the strip 46, in which the dash-dot lines illustrate the shape of the branched knife edges necessary to make the branched cut 130. In full 70 lines, I have shown the shape of the knives

necessary to make the cut 14. The strip 46 is fed so that the right hand part of the knife 114 will clear the leather and make the cut 131 constituting the leading edge of the strip. Said edge is then fed against the proper selected stop 5 17 or 48, whereafter the cut 130 is made, separating the half sole 132 from the strip and cutting part of the succeeding sole 133. By repeating the operation, similar half soles of completely shaped contour, may be cut from the strip in inverted 10 relation.

It will be understood that if desired, the central portion 115 of the knife blade 130 may be omitted so as to fail to separate the sole 132 from the sole 133, whereby a pair of mated soles 15 134 (Fig. 28) having reentrant outwardly diverging peripheral end edges, directed toward each other, is provided. Said mated soles may be sold to the trade as such to be later cut apart 20 by the user.

It will be understood, however, that the various waste pieces 119 are completely severed from the strip and thereby, the necessity for 25 later cutting the waste portions of the strip apart into smaller pieces suitable for other purposes, is avoided.

As illustrated in Fig. 12, the knife blades are so designed as to cut similar soles 132 in the same relative position from the strip, and to correspond to the shape of the branched cut 135. A single 30 35 branched blade only is therefore necessary. Said blade may be arranged on either one of the knife frames 41 or 42 of the machine and the other knife-carrying frame disconnected as hereinbefore described so that only a single knife operates upon the strip as it is fed against the stops. The machine may thereby be speeded up since the same knife does all the cutting. The method of cutting the strip consists in first clearing the 40 leading edge by means of the right hand branched portion of the knife blade, after which the strip is fed against the stop between each stroke of the cutting knife.

It will be understood that if desired, an intersecting or central portion of the knife blade may 45 be omitted in the manner described in connection with the mated soles 134 so as to produce the mated soles 136 of Fig. 26.

It will further be understood that in cutting the strip 46 of Fig. 11, or the strip 137 of Fig. 12, 50 unbranched knives may be so shaped as to cut a pair of mated soles 140 (Fig. 29) by means of a linear knife of the shape shown by the full line 138 of Fig. 29, operating alternately with a single similar knife shaped in accordance with 55 the full line 139. This will produce the leather piece 140 wherein the mated soles are joined together without an intermediate dividing cut with the waste pieces attached thereto.

It will be understood that in producing the 60 part 140, the strip is fed between each stroke a distance substantially equal to twice the width of a sole. After the cuts 138 and 139 have been made, repetition of the cut 138 after the strip is fed will produce a part 140 from the strip in inverted relation to the part shown in Fig. 29 but with the waste pieces attached. It will further be understood that the user may utilize the waste pieces which he cuts from the part 140 for 65 the purpose of cutting out heel lifts or the like. 70

As illustrated in Fig. 13, heel lifts as 141 may be cut from the strip 142 in the same manner and by the same types of knives as hereinbefore 75 described in connection with Figs. 11 and 12, the

branched knife taking the form of the branched dash-dot line 159.

As shown in Fig. 17, counters as 143 may be cut from the strip 144 by the use of a branched 5 knife blade of the shape of the branched dash-dot line 145.

In Fig. 18, I have illustrated the use of the same method for cutting shanks as 146 from the strip 147 by the use of a pair of branched blades 10 corresponding in shape to the branched dash-dot line 148 and to the full branched line 149, respectively.

In Fig. 31, I have illustrated the cutting of heel inserts which are intended to be imbedded in a rubber heel. The insert 150 is provided with protuberances and recesses at various points about which the rubber of the heel is compressed. Such heels are used for the purpose of eliminating rivets and washers so that the heel may be nailed to a shoe without the use of washers or rivets in a manner now known.

Said heel inserts may be cut from the strip 151 by means of a branched knife blade shaped in accordance with the dash-dot lines 152, 25 whereby a single branched knife is used and the strip fed between each stroke of the knife.

In what follows, I will describe my improved method in connection with the cutting of soles and half soles, though it will be understood that the same method can be applied to the cutting of heel lifts, counters, shanks and the like, as will be obvious from the above, and from Figs. 13, 17, 18 and 31.

Since it may be advisable in some cases to use what I will call unbranched knives, I have illustrated the use of such knives in Figs. 14, 15, 16 and 30. Referring to Fig. 14, I have there shown the use of an unbranched knife shaped to correspond with the full line 153, and a second knife shaped to correspond with the dash-dot line 154. In cutting soles by means of such knives, the leading edge of the leather is cleared by the right hand part of the knife corresponding to the cut 153 as shown by the full line 155. Immediately after the cut 155 is made and without permitting any movement of the strip or feed thereof, the second knife comes down to make the cut 154 which forms approximately half of the succeeding sole and rounds the heel part of the previous sole. It will be understood that the cut 154 does not reach completely to the edge of the strip, nor does the heel part thereof pass through any leather, since the leather has first been cleared so that part of the cut falls outside of the strip. The cut 154, furthermore, terminates inwardly of one edge of the strip at a point as 156 whereby the waste strip 157 remains attached.

After the cuts 155 and 154 have been made, the strip is then fed so that the leading edge 155 abuts against the proper one of the stops 47 or 48, whereupon the strip has been fed a sufficient distance so that the operation may be repeated. That is, the cut 153 is made after the strip has been fed and said cut passing the point 156 severs the sole from the strip with its attached waste piece 158. However, since the strip is not now fed, the next cut 154 severs the waste piece 158 so that the strip may now again be fed until the line 153 engages the proper stop. By repeating this operation, it will be seen that half soles 132 are cut. It will be remembered, however, that in this method of cutting the soles, two knives are used and that the strip is not fed until both knives have completed

their cuts unless indeed, the cutting positions of the knives are spaced apart so as to permit feeding of the strip between each cut.

In Fig. 15, I have shown the soles 132 in the same relation as in Fig. 11. One knife makes a cut corresponding to the sinuous full line 160. A second knife makes the cut corresponding to the dash-dot line 161, while the third knife makes the cut corresponding to the dash-double-dot line 162. After the leading edge of the strip has been severed by the cut 162, the strip is preferably not moved, but the cut on the line 160 is made whereby the waste piece 163 is severed. The strip is now moved until the edge 164 contacts with the proper stop, after which the cut on the line 161 is made, severing the sole 132 and the waste piece 165. The strip is now again moved until the severed edge on the line 161 engages the proper stop, whereafter the next cut 162 is made to sever the next sole and the waste piece 166. The strip is now again fed until its leading edge engages the same stop as that first engaged by the leading edge of the strip, whereafter the operations are repeated.

It will be noted that three knives are used, but that two of the knives operate preferably in succession without any intermediate feed of the strip, unless the cutting positions of the knives are spaced apart to permit intermediate feed of the strip. That is, the cuts on the lines 162 and 164 are preferably made while the strip is stationary, after which the strip is fed twice, first, for the cut 161 and again, to position the strip for the cut 162. 25

The machine of Fig. 34 is peculiarly adapted for cutting the soles in the manner just described, since three knives may there be used, operating in the desired manner. It will be understood, however, that the shapes indicated for the knives in Fig. 15 may be considerably varied, and still remain unbranched for the purpose of cutting out the soles as described. 35 40

Referring now to Fig. 16, I have there shown a method of cutting soles, each with two attached waste pieces. In this form of my invention, a single unbranched knife is used, shaped to make the cut 167. The sole 168 thus formed has attached at the upper left corner thereof, the waste piece 169, and at the lower right corner thereof, the piece 170. Said pieces, as has been previously indicated, may be utilized by the user for cutting out heel lifts and similar articles. In Fig. 16, the strip is fed after each cut by the knife the proper distance, as determined by the adjustable stops of the machine.

It is sometimes advisable to provide half soles 171 (Fig. 20) or other shapes with a waste strip 172 only partly attached thereto and partly severed therefrom. In such cases, the knives need not extend completely across the strip, but the strip may be so fed that part thereof adjacent an edge of the strip is not severed during the cutting operation. 60

In other words, part of the strip during the feeding thereof lies outside of the knife. Referring to Fig. 19, the dash-dot lines 173 illustrate a cut made by a suitably shaped branched knife, the end 174 of one of the blades terminating inwardly of the adjacent edge of the strip. A single branched knife is here used and the strip fed after each cut. It will be seen that a complete sole 171 together with a partly severed waste piece 172 is severed from the strip at each cut of the knife, and that the user may complete the partial cut 173 to leave a finished

half sole and to utilize the piece 172 for other purposes. It will also be understood that the sole 171 may have two or more partly severed waste pieces attached thereto as will be seen for example, from Figs. 11 and 16.

It will be understood that my improved knives may be made of any desired shape to make a multiplicity of cuts branching out, converging or diverging in different directions. For example, I have shown in Fig. 21 how four different shapes consisting of right and left soles, a pair of shanks, and a heel lift may be cut from the strip by means of only two knives, the strip being fed after each cut. One of the knives makes the dash-dot line cut 175 to sever the shank 177, and the waste pieces 176, 178, 183, and 179. The other knife may make the cut represented by the full lines 180 to complete the sole 181 and to sever the shank 182 and the heel lift 183 as well as to sever the waste pieces 184, 185, 187, 188 and 189, and to form half of the sole 190.

In other words, it being understood that the knife edge of my improved mechanism may be given any desired shape, a great variety of shapes variously positioned in many different ways may be cut from the strip or skin with considerable saving of material and of labor. In the succeeding description, some of the various arrangements of parts and consequently, the various knife shapes and method of feeding strips will be explained as examples.

Referring to Fig. 22, I have there shown a strip 191 of less than twice the width of a sole 35 yet used for cutting out two partly overlapping soles arranged substantially end to end from the width of the strip. Two knives are used and the strip is fed between each cut of each of the knives. One knife assumes the form shown by 40 the dash-dot lines 192, while the other knife assumes the form of the full lines 193. As will be obvious from the inspection of Fig. 22, four comparatively small waste pieces 194, 195, 196 and 197 are severed (or partly severed, as desired) from the strip, as are two soles 198 and 199. It will be noted that the knife 192 includes a curved branched member 200 extending toward the front of the machine while the knife 193 includes a similar member 201 oppositely curved. 50 Should it be desired to cut mated soles such as 136 from the strip 191, it will be understood that part of the edge of either the knife 192 or the knife 193 may be interrupted or omitted at the point 202 where the cuts made by said knives 55 would contact. It will also be understood that the knives may be made of less length than the width of the strip to leave the waste pieces partly attached and partly severed as has been hereinbefore described in connection with Fig. 19.

Referring to Fig. 23, I have there shown similar soles arranged in reversed relation to be cut from the strip 203 by suitable branched knives. One of said knives is shaped to make the cut shown by the dash-dot lines 204, while the other 65 knife is shaped to make the cut 205 shown by the full lines. The knife making the cut 205 also cuts out the heel lifts 206 and 207. The knives cut alternately and the strip is fed between each cut.

In Fig. 24, I have shown a means and method 70 other than that disclosed in Fig. 22, for cutting out two soles from the width of a strip. These soles may be mated soles attached together as in Fig. 26, or they may be joined in reversed position as at 134 (Fig. 28). If the knife is properly

shaped, a single branched knife is sufficient to sever two soles at each stroke. The knife takes the form of the dash-dot lines 208, each stroke of which cuts one-half of one set of soles to sever them from the strip and simultaneously 5 forms the other half of the succeeding member of soles while cutting out the waste strips 209, 210 and 211. It will be understood that these soles may be cut with two knives, if desired.

In Fig. 25, I have shown an arrangement of 10 soles similar to that of Fig. 24, excepting that the soles are arranged end to end across the strip to make the width of the strip twice that of the length of the sole. In this case, two branched knives are used, one of the shape of the dash-dot 15 lines 212, and the other of the shape of the full lines 213. On the stroke of each of the knives, two complete soles are cut out as well as three waste pieces, as will be clear from inspection of the figure, since each knife cuts one-half of a 20 pair of soles and simultaneously cuts the other half of the succeeding pair.

In order to save material, it will be clear that the rear edge 214 of the sole may be curved as at 215, (Fig. 27), if desired, and that the knives 25 may be so shaped as to cut the soles in the same relative position on the strip to produce the mated soles 216. As shown in Fig. 25, however, if a gap is left in one of the knives as at 217, the mated soles 134 (Fig. 28) are formed. The waste piece may also be only partly severed and may remain partly attached to the mated soles by terminating the knives somewhat short of the edges of the strip, as has been previously explained. 35

Referring to Fig. 30, I have there shown how unbranched knives may be used in cutting a wide strip so that two soles arranged end to end are cut therefrom. In this case, one of the knives is shaped to make the cut shown by the 40 dash-dot line 218 across the strip 219. Preferably without feeding the strip, the second knife now operates to make the cut shown by the full line 220, thereby severing two soles from the strip. It will be understood that a portion 221 45 of the knife making the cut 218 is omitted so as to retain the sole 222 attached to the strip before the cut 220 is made, the second knife only, serving to sever the soles and the waste pieces from the strip. I will also be understood that 50 the strip may be fed between cuts if the cutting positions of the knives are respectively spaced the proper distance.

While I have above described certain shapes and arrangements of shoe parts and methods 55 of cutting said parts from strips, I have referred hereinbefore only to strips of uniform width and having parallel edges, which strips are previously cut from the hide.

I will now describe the methods of cutting 60 parts such as soles from the hide with maximum economy of leather and by means of the types of knives now used on the blocking machine. This form of my invention contemplates the cutting of the hide into strips having irregularly 65 shaped edges, which are of predetermined form. As shown in Fig. 32, I have illustrated part of a hide with the soles appearing thereon as though already cut though it will be understood that the hide is not marked in carrying out my invention. However, the hide is first cut into strips by stripping cuts indicated by the heavy lines.

The cut 225 is made by the usual stripper but the ordinary straight stripping knife is not used. The knife of the well-known stripping machine 75

is shaped to make said cut 225 of the desired irregular outline. Thereafter, the hide is moved to a suitable stop and the similar stripping cut 226 is made, thereby cutting off a strip 227 from the hide. In said strip, the soles are partly formed by the stripping cut and it now remains only to make the remaining cuts to separate the soles. It will be seen that only two unbranched knives are necessary to make said cuts. The 10 shape of one knife is illustrated by the dash-double-dot line 228, while the shape of the second knife is illustrated by the dash-single-dot line 229. As shown in Fig. 35, the strip is fed in the direction of the arrow, one edge resting 15 against the upright face 230 of the strip guide 231. In this case, the knives cut alternately and the strip is fed against the proper stop 47, 48 or 248 after each cut.

Where it is desired to cut two pairs of mated 20 soles at a time from the hide, (Fig. 33), the strip is cut from the hide in the same manner but is of twice the width of the strip 227. A single unbranched knife shaped in accordance with the dash-dot lines 232 is used, and the strip is fed 25 between each cut of the knife. Each cut therefore severs two pairs of mated soles 233 at each stroke.

It will be understood that by shaping one or 30 more knives according to predetermined cutting lines, a great variety of shapes in a variety of different positions may be cut from a strip of leather while making provision for defects and while permitting variations in the width of the parts cut in accordance with the thickness of the 35 leather.

It will be seen that I have provided novel cutting methods and means for carrying out said methods, and that my invention is well adapted to meet the severe requirements of practical use.

40 While I have shown and described certain specific embodiments of my invention, I do not wish to be understood as limiting myself thereto but intend to claim my invention as broadly as may be permitted by the state of the prior art and the 45 scope of the appended claims.

I claim:

1. In mechanism of the character described, a 50 knife provided with a cutting edge of predetermined shape, means for oscillating said knife alternately in opposite directions for cutting parts of predetermined shape from a strip of leather, an aligning stop for said strip arranged at the rear of the machine, and means arranged at the 55 front of the machine and operatively connected to said stop for adjusting the stop forwardly and rearwardly during operation of the knife including an adjusting handle, and spring-pressed means for normally maintaining said handle in its adjusted position, said means permitting the operator to vary the width of the parts cut from the strip in accordance with the varying thicknesses of the strip and the defects therein.

2. In mechanism of the character described, a 60 plurality of knives each provided with a cutting edge of predetermined shape, means for operating each of said knives to make cuts in succession in a strip, means for aligning said strip, and means for adjusting said aligning means including a spring-pressed detent, and a recessed member cooperating with the detent to normally maintain the detent in the position in which it is set in the member.

3. In a machine of the character described, a 65 knife, means for oscillating the knife to make a

series of cuts in a strip, means for supporting the strip for manual intermittent movement through the machine during the oscillation of the knife, an aligning stop for the strip, a side guide for the strip, and means for adjusting the position of 5 the stop during operation of the knife including a spring-pressed detent, a support for the detent, and means for operatively connecting the detent to the stop.

4. In mechanism of the character described, a 10 knife support, means for oscillating said support alternately in opposite directions, a stop adapted to align the leading edge of a strip, a knife having branched cutting edges pivoted to the knife support, said knife being shaped to sever waste 15 pieces from the strip, means for adjusting the stop during the manual feeding of the strip through the mechanism to vary the widths of the parts cut from the strip, and means associated with the knife for ejecting said waste pieces. 20

5. In mechanism of the character described, means for aligning the leading edge of a strip of leather, means for adjusting the aligning means, means for making cuts in said strip comprising an oscillatory knife, having branched 25 cutting edges shaped to make a series of cuts spaced from each other throughout the width of the strip but contacting for a comparatively short distance at points adjacent the center of the strip, and means associated with the knife to 30 eject waste pieces cut from said strip.

6. In a leather cutting machine, a knife having a pair of tangent arcuate cutting edges, a pivoted holder for the knife, means for oscillating said holder about its pivot to carry the knife toward and from a strip of leather while maintaining the knife edges lowermost, means for aligning an edge of the strip to permit manual feeding of the strip through the machine while in contact with the aligning means, and to permit selection of the points of said strip where cuts are to be made by said knife, means for aligning the leading end of the strip during said manual feeding of the strip in one direction only and with the same face uppermost, and means for adjusting said end aligning means during said feeding to vary the width of the parts cut from the strip in accordance with the varying thicknesses of the strip and the defects therein. 40

7. In a machine of the character described, a 50 branched knife having a plurality of cutting edges meeting each other, an oscillatory frame carrying said knife, means for swinging said frame toward and from a strip to make cuts in said strip, means for aligning an edge of the strip, means for aligning the leading end of the strip, and means within reach of the operator for adjusting the end aligning means while the machine is in operation to vary the widths of the parts cut from the strip in accordance with the varying 55 thicknesses of the strip and parts cut from the strip in accordance with the varying thicknesses of the strip and the defects therein.

8. In a machine of the character described, an 60 oscillatory knife support, and a knife carried by said support and being of sufficient length to cut completely across a strip of leather to produce half soles therefrom by longitudinally spaced cuts made by said knife in said strip, said knife comprising a longer edge concave outwardly, and a second shorter edge concave outwardly and tangent to the first-mentioned concave edge intermediate the extremities of said edges, the longer concave edge beyond one extremity of the shorter 65 70 75

- edge being rounded through an angle of less than 90° and adapted to extend to an edge of the strip, and the other ends of said concave edges being in alignment and adapted to extend to the other
- 5 5. edge of the strip, the shorter edge partly but not completely severing a waste piece from the strip when pressed through the strip from one given face of the strip to the other.
9. In a machine of the character described, an oscillatory knife support, and a knife carried by said support and adapted to cut completely across and to successively contact with the same face of a strip of leather to produce a pair of united and mated half soles therefrom in two operations,
- 10 15. said knife comprising a pair of spaced V-shaped cutting edges arranged with the apices thereof in transverse alignment and adjacent each other.
10. In a machine of the character described, an oscillatory knife support, and a knife carried by said support, said knife comprising a pair of cutting edges each rounded at one of its ends, said edges being convex toward each other and tangent at a point substantially midway between the ends thereof and being of sufficient length to cut half soles completely across a strip of leather by cuts made through the same from one given face thereof to the other, whereby a pair of triangular waste pieces are severed from the strip, and the front edge and part of the rounded end of one half sole and the rear edge and part of the rounded end of another half sole are cut simultaneously, the edge of the strip forming the straight ends of the half soles.
- 15

EMANUEL BERKOWITZ.
